PISTON SKIRT STABILIZER

Melvin W. Marien, Richmond Heights, Mo., assignor to Ramsey Corporation, St. Louis, Mo., a corporation of Delaware

Application September 30, 1950, Serial No. 187,790

8 Claims. (Cl. 309—12)

1

My invention has relation to improvements in piston skirt stabilizers (sometimes called piston skirt expanders) and it consists in the novel features of construction more fully set forth in the specification and pointed out in the claims.

Piston skirt stabilizers (or expanders) have generally been used heretofore for the rehabilitation of worn engines in order to overcome excessive clearance between the piston and the cylinder due to wear. The present invention is concerned more particularly with stabilizers to be initially inserted in the pistons so as to prevent any collapse of the piston skirt and compensate for wear between the piston and cylinder as it occurs. Obviously the stabilizer must be securely mounted within the piston skirt so as not to become displaced during the operation thereof and at the same time should be of a construction that will permit easy and quick application.

These advantages, together with others inherent in the invention, will be better apparent from a detailed description of the invention in connection with the accompanying drawings, in which:

Fig. 1 is a combined side elevation and middle longitudinal section of a typical piston showing my improved stabilizer mounted therein; Fig. 2 is a bottom plan of the piston showing the stabilizer in place; Fig. 3 is a vertical longitudinal section taken on a plane indicated by the line 3—3 in Fig. 1; Fig. 4 is a cross-sectional detail through my improved stabilizer taken on the line 4—4 in Fig. 1; Fig. 5 is a fragmentary view of the piston skirt showing one of the bosses between which the stabilizer is mounted; Fig. 6 is a section similar to that shown in Fig. 4, but of a modified form of construction; Fig. 7 is a side elevation of the modification shown in Fig. 6 contracted prior to insertion within the piston skirt; Fig. 8 is a cross section of a further modified form of the invention; Fig. 9 is a side elevation of the modification shown in Fig. 8; and Fig. 10 is a still further modified form of the invention shown in longitudinal section.

Referring to the drawings, P represents a piston connected to a connecting rod R (dotted in Figs. 1 to 3 inclusive) by a wrist pin W. There are a pair of my improved stabilizers (or expanders) E, E inserted within the piston skirt S for the purpose of exerting pressure thereon in a direction at right angles to the axis of the wrist pin. This is the direction of the thrust during the operation of the piston and if the latter is to collapse it will do so in this plane. The use of a stabilizer (or expander) to prevent piston collapse is not new. However, the stabilizer form-

2

ing the subject of the present invention is to my knowledge novel both in its general construction and in the manner of its application to the piston. Since each stabilizer E of the pair is identical, only one will be described.

It will be noted that there are two pairs of bosses 1, 1 disposed in opposing relation within the piston skirt S and spaced sufficiently so that when the expanders E, E are mounted between opposing bosses they will straddle the connecting rod R (Fig. 3).

Each of the bosses 1, 1 is provided with a socket 2, in which socket the expander E is mounted in the following manner: The expander E comprises a tube 3 provided with threads 4 at one end of which is passed an adjusting nut 5. Disposed within the threaded end of the tube 3 is a cylindrical plug 6 terminating in a flange 7 from which extends a pin 8. The pin 8 is lodged in one of the sockets 2. A second plug 9 is disposed in the opposite end of the tube 3, said plug also having a flange 10 and a pin 11 which fits in socket 2. There is a coiled spring 12 disposed over the tube 3 and confined between flange 10 and adjusting nut 5 so as to exert tension expansively against the plug 6 and plug 9. By adjusting the position of the nut 5 the tension on spring 12 may be varied either to exert greater pressure on the piston skirt or lesser pressure as the requirements demand.

It is apparent from the foregoing that considerable spring resilience may be built into the piston skirt by the use of a pair of stabilizers as shown in Figs. 1 to 4 inclusive. It is also apparent that the stabilizers are very easily inserted in position since the tension on spring 12 may be relaxed prior to insertion and increased to the necessary degree thereafter.

In Figs. 6 and 7 I show a somewhat modified form of invention in which three cylinders 15, 16, and 17 are arranged in telescopic relation, the terminal cylinders 16 and 17 having openings 18 and 19 formed in their extremities so as to receive the bosses 20 and 21 within the piston skirt S'. The inner margins of the cylinders 16 and 17 are swaged over as indicated at 22 and 23 so that they may be held together by hooks 24 to overcome the tension of spring 25 prior to the insertion of expanders in the piston skirt S'. Of course, after the expanders have been inserted in position the hooks 24 may be snipped so as to permit the spring 25 to expand the cylinders 16 and 17 against opposite surfaces of the skirt S'.

In Fig. 8 I show a modification wherein two identical cylinders 26, 26, having their inner

ends closed and their outer ends open to receive bosses 27, 27 formed in the piston skirt S'', are connected by a nut 28. Obviously the cylinders 26, 26 are provided with right and left hand threads and the nut is similarly threaded so as to operate as a turnbuckle. In the modification shown in Fig. 10 there are but two cylinders 30, 31 telescopically arranged, the outer cylinder 30 having slots 32, 32 formed in it. The purpose of the slots is to permit pins 33, 33 fixed in cylinder 31 to project upwardly for cooperation with lugs 34, 34 formed on cylinder 30, whereby the cylinders may be contracted to permit of easy insertion within the piston skirt S'''.

It should be readily apparent that the invention is readily susceptible of many modifications, and I do not wish to be restricted to any of the specific forms herein shown.

Having described my invention, I claim:

1. A piston stabilizer comprising a pair of tubular housings, a third tubular member in telescopic relation therewith, a coiled spring disposed within the assembled housings and suitable formations on the inner extremities of said pair of housings to receive a tool whereby said housings may be contracted over the pressure of said spring.

2. A piston stabilizer comprising telescopically arranged tubular members, a coiled spring disposed within said tubular members and tool receiving elements projecting from the periphery of said members whereby they may be compressed over the tension of said springs.

3. A self-contained piston stabilizer comprising a capsule having extensible and contractible end portions, end faces on said end portions shaped and sized for engagement with piston retainers to hold the capsule in spanning relation across the skirt of a piston, spring means in said capsule urging said end portions outwardly for causing said end faces to exert an expanding force on the piston skirt, peripheral protuberances on the end portions, and means coacting with said protuberances for retaining the end portions in assembled capsule forming relation.

4. A piston stabilizer to be mounted within and transversely of the skirt of the piston to expand the piston skirt comprising telescopically arranged members with end portions arranged and disposed to associate and cooperate with stabilizer retaining portions on said piston skirt, a coil spring concentrically and telescopically arranged within said telescopically arranged members and retained so arranged by means forming part of the end portions of said members and end portions of said coil spring contacting only said last mentioned means.

5. A piston stabilizer to be mounted within and transversely of the skirt of the piston to expand said skirt comprising telescopically arranged members with outer end portions arranged and disposed to associate and cooperate with stabilizer retaining portions on said piston skirt, a coil spring concentrically and telescopically arranged within said telescopically arranged members and retained and so positioned by means forming part of the said outer end portions of the members, the ends of said coil spring contacting only said last mentioned means, and tool receiving means on the periphery of said

members whereby they may be compressed over the tension of said spring.

6. A piston stabilizer to be mounted within and transversely of the skirt of the piston to expand the said skirt comprising a pair of telescopically arranged members with swaged-in outer end portions arranged and disposed to associate and cooperate with stabilizer retaining portions on said piston skirts, a coil spring concentrically and telescopically arranged within said pair of telescopically arranged members and retained and so positioned by said swaged-in outer end portion of said members, the ends of said coil spring contacting only said swaged-in outer end portion, and tool receiving elements projecting from the periphery of said members whereby they may be compressed over the tension of said spring.

7. A piston stabilizer to be mounted within and transversely of the skirt of the piston to expand the said skirt comprising a pair of telescopically arranged members with swaged-in outer end portions arranged and disposed to associate and cooperate with stabilizer retaining portions on said piston skirt, a third member telescopically arranged and disposed within said pair of members, said pair of members and said third member forming a housing containing a coil spring concentrically and telescopically arranged therewithin and retained so positioned by said swaged-in end portions of said pair of members, the ends of said coil springs contacting only said swaged-in end portions and suitable formations on the inner extremities of said housing to receive a tool whereby said housing may be contracted over the pressure of said spring.

8. A piston stabilizer to be mounted within and transversely of the skirt of the piston to expand the said skirt comprising a pair of telescopically arranged members with swaged-in outer end portions arranged and disposed to associate and cooperate with stabilizer retaining portions on said piston skirts, a third member telescopically arranged within said pair of members, said pair of members on said third member forming a housing including therewithin a coil spring concentrically and telescopically associated therewith, said coil spring retained so associated and positioned by said swaged-in outer end portions of said pair of members, the ends of said coil spring contacting only said swaged-in outer end portions, said pair of members having swaged-out inner extremities receiving hooks retaining the parts of the housing and stabilizer in proper association and in capsule form against the tension of the spring.

MELVIN W. MARIEN.
